[57] CLAIM

The ornamental design for a tape drive, as shown and described.

DESCRIPTION

FIG. 1 is a top front isometric view of the tape drive showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view thereof, the left side being a mirror image;

FIG. 7 is a front elevational view of the control panel on a greatly enlarged scale, the remainder of the tape drive being omitted for convenience of illustration.

FIG. 2

FIG. 1

790768 FIG. 3

FIG. 4

FIG. 5

FIG. 6

FIG. 7
